ATTORNEY

UNITED STATES PATENT OFFICE.

CARL K. HAUGEN, OF PORTLAND, NORTH DAKOTA.

TOY.

1,290,987.

Specification of Letters Patent. Patented Jan. 14, 1919.

Application filed May 14, 1918. Serial No. 294,420.

To all whom it may concern:

Be it known that I, CARL K. HAUGEN, a citizen of the United States, residing at Portland, in the county of Traill and State 5 of North Dakota, have invented certain new and useful Improvements in Toys, of which the following is a specification.

This invention relates to toys, and more particularly to manually propelled children's vehicles.

The object of the invention is to provide a cheaply constructed, simple, strong toy of this character in which a child can ride and propel and guide it with his feet.

Another object is to provide a toy of this character the body of which has foot supports disposed convenient for use by the rider when coasting, said body being cut out to facilitate propelling of the car and to 20 provide the foot supports.

With the foregoing and other objects in view, which will appear as the description proceeds, the invention resides in the combination and arrangement of parts and in 25 the details of construction hereinafter described and claimed, it being understood that changes in the precise embodiment of the invention herein disclosed may be made within the scope of what is claimed without departing from the spirit of the invention.

In the accompanying drawings:

Figure 1 represents a side elevation of the toy constituting this invention,

Fig. 2 is a plan view thereof, and

Fig. 3 is a front elevation with parts broken out.

In the embodiment illustrated, a flat body 1 is shown composed of a board or other suitable material with a seat 2 formed at the 40 rear and a hoodshaped member 3 at its front to simulate the appearance of an automobile. Extending around the rear portion of the seat 2 is an upstanding flange 4 to form a back or abutment for the rider.

A hand grip 5 shaped to represent a steering wheel extends upwardly and rearwardly from the hood 3 and is mounted on the inclined post 6 which simulates the steering post of an automobile.

The side edges of the body or board 1 are cut away in advance of the seat 2 as is shown clearly in Fig. 2 so as to render the body narrow at this point to facilitate the propulsion of the vehicle by the engagement of the rider's feet with the surface over which it is passing and the front ends of said cut

away portions form foot supports as shown at 1^a on which the rider's feet may rest when coasting.

This body 1 is mounted on front and rear standards, the rear standard 7 being in the form of an inverted truncated V-shaped member composed of heavy strap iron with a cross bar 8 at its truncated end bolted to the rear portion of the body under the seat 60 2 and a cross bar 10 braces and connects the members 9 of said standard 7 as shown clearly in Fig. 3. These members 9 diverge toward their lower ends and have their terminals inturned to form attaching feet as 70 shown at 9^a for rollers 17 which are swiveled thereto and made of any suitable or desired construction, being here shown in the form of casters.

A heavy metal strap 11 is arranged longitudinally on the lower face of the body 1 and bolted thereto, its rear end being downwardly inclined as shown at 12 and bolted to the cross bar 10 which connects the members 9 of the standard 7. This inclined portion 12 of the strap 11 operates to brace the vehicle at its rear end. The front end of this strap 11 extends to the front of the vehicle and is then extended downwardly at right angles to form the front standard 13 80 85 which is positioned midway the width of the body and carries at its lower end the swiveled roller 17 similar to those used at the rear of the vehicle. This standard 13 is bent laterally inward as shown at 14 to form 90 a support for the roller 17 and then extends upwardly and rearwardly at an incline as shown at 15 to form a brace having its terminal 16 bolted to the body of the strap 11 at a point directly below the inner end of 95 hood 3 (see Fig. 1).

From the above description it will be obvious that this vehicle, while very simple in construction is strong and serviceable and may be cheaply constructed, having few 100 parts to become broken or disconnected.

In the use of the vehicle, the child will of course sit on seat 2 with his legs straddling the cut out body portion in advance of the seat so that his feet may engage the surface 10^a over which the vehicle is to travel, and it is to be understood that he will use his feet for both propelling and guiding the vehicle, the hand grip 5 being simply used when coasting if found necessary.

The foregoing description and the drawings have reference to what may be consid-

ered the preferred or approved form of my invention. It is to be understood that I may make such changes in construction and arrangement and combination of parts, materials, dimensions, etc., as may prove expedient and fall within the scope of the claimed invention.

Having thus fully described my invention, what I claim as new and desire to secure by Letters Patent, is:—

In a device of the class described, a body having a truncated V-shaped member arranged transversely of its rear end to form depending standards with rollers swiveled

to their lower ends, a bracing strap extended longitudinally of the body and secured thereto, with its rear end downwardly inclined and secured to the standards at the rear of the vehicle, and its front end shaped to form a depending roller carrying standard with a bracing member connecting it to the body of the vehicle.

In testimony whereof I affix my signature in presence of two witnesses,

CARL K. HAUGEN.
